UNITED STATES PATENT OFFICE.

AXEL RUDOLPH SALSTROM, OF JERSEY CITY, NEW JERSEY.

RAZOR-BLADE SHARPENER.

1,425,290.

Specification of Letters Patent. Patented Aug. 8, 1922.

Application filed July 8, 1919. Serial No. 309,328.

To all whom it may concern:

Be it known that I, AXEL RUDOLPH SALSTROM, a subject of the King of Sweden, residing at Jersey City, in the county of

5 Hudson and State of New Jersey, have invented certain new and useful Improvements in Razor-Blade Sharpeners; and I do hereby declare the following to be a full, clear, and exact description of the invention, 10 such as will enable others skilled in the art to which it appertains to make and use the same.

The present invention relates to improvements in razor blade sharpeners and has for 15 an object to provide a compact machine in which the movable parts are contained in a casing for avoiding the likelihood of an operator's hands coming in contact with and sustaining injury by such parts. 20 Another object of this invention resides in providing an encased machine, in which a blade holder is arranged to slide into and out of the casing to receive a blade to be sharpened and with which is associated 25 parts that limit the movement of the holder and prevent its becoming disconnected from the casing.

It is a further object of the present invention to provide a sharpening machine 30 for razor blades and the like, which embodies improved driving means for the sharpening means, and improved mechanism for oscillating the blade holder, which includes parts for securing the holder 35 against oscillation in a neutral position between the sharpening rolls when the holder is withdrawn from the casing to permit the removal of the blade.

With the foregoing and other objects in 40 view, the invention will be more fully understood from the following detailed description taken in conjunction with the accompanying drawings, which illustrate a single mechanical embodiment of which the 45 invention is susceptible, wherein like reference characters refer to like or corresponding parts throughout the several views, and in which,

Fig. 1 is a perspective view taken from 50 one end, of a sharpening machine constructed in accordance with the present invention.

Fig. 2 is a similar view taken from the opposite end.

Fig. 3 is a plan view of the complete 55 machine, with the blade holder drawn out and the casing shown in dotted lines.

Fig. 4 is a side view of the same.

Fig. 5 is an end view looking from the left in Figs. 3 and 4 and with the end cap removed. 60

Fig. 6 is a similar view seen from the other end.

Fig. 7 is a central horizontal section through the machine.

Fig. 8 is a central vertical section through the machine. 65

Fig. 9 is a section taken on the line 9—9 in Fig. 4 showing the oscillating mechanism for the blade holder in one position.

Fig. 10 is a similar view showing the oscillating mechanism in a subsequent position. 70

Fig. 11 is a cross sectional view taken on the line 11—11 in Fig. 7, showing the blade holder and blade in the horizontal neutral 75 position.

Fig. 12 is a section taken on the line 12—12 in Fig. 7 and showing the blade holder and blade in the neutral position.

Fig. 13 is a view similar to Fig. 11 with 80 the blade holder and blade in a canted position.

Fig. 14 is a view similar to Fig. 12 also showing the blade holder and blade canted to one side. 85

Fig. 15 is a longitudinal section through one of the sharpening rolls.

Fig. 16 is a cross section through one of the cams and its actuating gear.

Fig. 17 is a perspective view of the upper member of the blade holder and the slotted stop frame. 90

Fig. 18 is a similar view of the lower sliding member of the blade holder.

Fig. 19 is a perspective view of the bracket and spring arms of the oscillating mechanism. 95

Fig. 20 is a similar view of the key for controlling the stop mechanism.

Fig. 21 is a perspective view of the crank 100 employed, and

Fig. 22 is a fragmentary perspective view showing the connection between the discs and bars.

Referring more particularly to the drawings, 1 designates a tubular body of thin metal, which, together with flanged caps 2 and 3 fitting over the open ends of the body, forms a casing for enclosing the various parts of the machine. 105

As I have constructed the device in practice, the approximate actual size of which

is illustrated, this tubular body 1 is with advantage made substantially oval in cross section that it may the better lend itself to the grasp of one of an operator's hands, in which the machine is held, while the other hand is left free to rotate a crank for developing the necessary power to turn the sharpening rolls and actuate the other mechanism. The casing serves the further purpose of 10 excluding dust and other foreign matter from the interior moving parts and acts as a guard or shield to prevent the operator's hands coming in contact with the mechanism or razor blade.

15 Within the casing is a frame for supporting the various parts, and as shown in Figs. 3, 4, 7 and 8, this frame is composed of a number of oval discs connected by bars 4. At the right hand end of the machine as it 20 appears in these figures there are shown a pair of discs 5 and 6; while at the opposite end are three discs 7, 8 and 9, all being held apart to provide spaces therebetween for containing the several mechanisms. Four 25 bars 4 are used in the present machine to hold the discs together and at the proper interval apart, although a greater or lesser number might be employed, and as seen in Fig. 22 the connection between the discs and 30 bars is preferably made by producing slots 10 in the edges of the discs and slots 11 in the adjacent faces of the bars 4, the slots being interfitted in the manner shown so 35 that the outer faces of the bars may lie flush with the edges of the discs and form a smooth uniform exterior, over which the tubular body 1 may with facility be slipped. Screws or other fastening means 12 taking 40 into the end discs 5 and 9 as appears in Fig. 7 are used to hold the caps 2 and 3 in place.

A pair of upper shafts 13 and 14 and a pair of lower shafts 15 and 16 are journaled in the discs 6, 7, 8 and 9, and as indicated in Figs. 4 and 5 the ends of the shafts 13 45 and 16 are made to project a distance beyond the disc 9 to form stops for preventing the cap 3 binding against the gearing that rotates the shafts, although this purpose would probably be to some extent suberved 50 by the ends of the bars 4.

Pairs of sharpening rolls 17, 18 and 19, 20 55 are mounted on the shafts 13, 14, 15 and 16, the preferred construction of the rolls being shown in Fig. 15, wherein 21 designates an inner hollow cylindrical shell and 22 an outer strip of leather or other honing material spirally wrapped about the shell 21 and secured thereto as by adhesive or other appropriate means. The spiral strip 22 when 60 rotated in contact with the blade not only moves at right angles to the edge of the blade but also progresses longitudinally of the blade edge and causes a smooth and uniform sharpening of the edge throughout.

65 Heads 23 and 24 are fitted in the ends of

the shell 21 and are perforated to receive the shafts. A pin 25 passes through the shell 21 and enters the head 23 to secure same in place. The opposite head 24 is held by a set screw 26 which projects in the perforation 70 in this head and, when the roll is mounted on its shaft, such screw 26 serves to make the roll fast thereon.

Referring to Fig. 5 the shafts 13 and 15 carry gear wheels 27 and 28 which are in mesh. The shafts 14 and 16 also carry similar gear wheels 29 and 30, which mesh together but do not mesh with the wheels 27 and 28. These various gear wheels are shown in dotted lines as they are comprised 80 in the space between the discs 8 and 9 as is clear from Figs. 3, 4, 7 and 8.

Still referring to Fig. 5 the shafts 14 and 15 are provided with pinions 31 and 32 which are in mesh with a central gear wheel 33 on a stub shaft 34 journaled in the discs 8 and 9. The pinions 31 and 32 and gear wheel 33 are shown in full lines in this Fig. 5 as they are in front of the disc 9 for which see Figs. 3, 4, 7 and 8.

90 The shaft 15 is extended and passes through the cap 3 to the exterior of the casing, as appears in Figs. 1, 3, 4 and 7, where it is exposed to receive a crank. The exposed end of the shaft 15 is furnished with a pin 35 for engagement with a crank, such for instance as shown in Fig. 21, where the arm 36 of the crank is provided with a handle 37 at one end projecting in one direction and a bearing sleeve 38 at the other end 100 extending in the opposite direction. The outer end of the sleeve is made after the fashion of a cam with an inclined wall 39 and an abrupt shoulder 40 lying in the direction of the axis of the sleeve and connecting the inner and outer ends of the inclined or partially spiral wall 39.

105 In use, the crank is so fitted to the machine that the sleeve engages over the projecting end of the shaft 15 and when turned 110 in a right hand or clock-wise direction, the shoulder 40 of the crank will take against the pin 35 and transmit rotation to the shaft 15. This clock-wise direction is the one to cause the various rolls to rotate with proper 115 relation to the edges of the blade and, were the rolls to be rotated in an opposite direction injury would be done both the blade and the rolls. Should the crank be rotated in the opposite direction in an attempt to 120 improperly turn the rolls the inclined or spiral face 39 will engage the pin 35 and cause the sleeve 38 to be shifted axially on the shaft 15 away from such pin so that no effective engagement between the crank and 125 shaft may be obtained in this direction.

When the crank is correctly rotated in the clock-wise direction the result on the gearing is shown by the arrows in Figs. 5 and 13, in the latter of which figures it is made plain 130

that the various honing surfaces, each moves in a direction from the centre of the blade toward and beyond the edge thereof.

The blade to be sharpened is indicated at 5 41 as being the usual double edged blade, used for instance in the Gillette safety razor, although the invention is applicable for use in connection with other types of blades. The blade 41 is adapted to be seated on the 10 lower member 42 of a two-part holder, which is provided with pins 43 in the upper flat face thereof in order to receive the perforations in the blade and hold the blade against displacement.

15 The holder is more particularly shown in Figs. 17 and 18 and besides the lower member 42, consists also of an upper member 44. The two members 42 and 44 are complements and are adapted to clamp the blade

20 41 therebetween and hold the same securely while being sharpened. These two members are made preferably in a cylindrical form which is split longitudinally. The member 44 has a reduced journal 45 at one end fitted 25 in the disc 7, while the other ends of the members 42 and 44 are journaled in the discs 5 and 6. The lower member or holder proper is longitudinally slidable on the upper member 44 and has at its inner end a pair of 30 curved claws 46, which lightly clamp over the edges of the upper member and freely slide thereon. A shoulder 47 on the extreme inner end of the member 42 is arranged to enter a notch 48 in the trunnion 45 as shown

35 in Fig. 8, whereby to sustain this end of the lower member when pushed home and to take the weight off the claws 46 while the operation of sharpening is being carried out.

40 Figs. 3 and 4 show the position of the member 42 when drawn out, openings being made in the discs 5 and 6 and an opening 49 in the cap 2 to permit same. The notch 50 shown in Fig. 2 is to allow of the passage 45 of the tops of the pins 43, while the side slots of the opening 49 permit the removal of the cap 2 over the finger piece 51 that is formed at the outer end of the lower member 42 of the holder. When drawn out, the 50 member 42 clears the casing and the sharpened blade may be removed and another substituted. The claws, however, engage against the wall of the cap 2 above the slot 49 and prevent the member 42 from becoming disconnected from the machine, while maintaining such member in proper position 55 to be slid back when a subsequent blade has been placed thereon.

60 The blade holder including both upper and lower members is adapted to be oscillated and this is accomplished in the following manner:

A pinion 52 is mounted on the inner end of the stub shaft 34 and as shown in Figs. 65 9 and 10 this pinion meshes with and drives

two other pinions 53 and 54 loosely mounted respectively on the shafts 15 and 16. These pinions 53 and 54 carry cams 55 and 56 set at 180° apart, the cams and pinions being preferably constructed in one piece as 70 shown in Fig. 16.

The cams 55 and 56 alternately engage spring arms 57 and 58 curved at their lower free ends where they encounter the cams, and being preferably formed in one piece 75 in the shape of a yoke, which is suspended on the overhanging end 59 of a bracket 60 shown in Fig. 19. The bracket has perforations 61 fitting over pins 62 on a flattened portion 63 of the upper member 44 80 of the blade holder and a central perforation 64 adapted to register with a threaded opening 65 in the portion 63, which receive a screw 66 shown in Figs. 7 and 8.

The cams alternately striking the spring 85 arms 57 and 58 set up a rocking movement in the blade holder and blade and cause the edges of the blade to be brought in contact with first one set of rolls 17 and 20 as appears in Fig. 13 and subsequently in engage- 90 with the other set of rolls 18 and 19, and the resilient character of the arms 57 and 58 causes the blade to be firmly, yet yieldingly, pressed against the honing surfaces.

As seen in Fig. 17, the holder is provided 95 with a stop frame 67 slotted as indicated at 68 and oscillating between the discs 5 and 6. A key 69 shown in Fig. 20 has a thumb piece 70 by which it may be turned, and fingers 71 projecting in opposite directions. 100 The fingers lie within the slot 68 of the stop frame as shown in Figs. 8, 12 and 14, and when in the position illustrated in Fig. 14 the frame and the holder are free to oscillate. By turning the key 69 through a quarter of a revolution, the fingers 71 are brought to the position shown in Fig. 12 and the frame and holder can no longer be rocked. If the crank is turned when the parts are in 105 this position, the spring arms 57 and 58 110 will yield and allow the cams 55 and 56 to be turned without affecting the blade holder.

The position of the key 69 is shown in Fig. 2, it extending through a slot 72 in the cap 2, which permits removal of the cap 115 over the thumb piece 70, but the slot is smaller than the fingers 71 and hence the key cannot escape or be lost. The shank of the key is projected inward beyond the arms, and when in place as shown in Fig. 8 this 120 portion of the shank has a bearing in the disc 6.

The purpose of the stop mechanism is to hold the blade holder in a central neutral position with the blade out of contact with 125 the rolls as appears in Figs. 11 and 12. In this position the blade holder may be withdrawn without incurring the danger of injury to the rolls or blade.

The object in having the cams 55 and 56 130

loosely mounted on the shafts 15 and 16 and in employing separate gearing to rotate the same, is to secure a reduction in the rotation of the cams as compared with the shafts in order that the blade edges may be held for an extended period of time in contact with the rapidly moving rolls.

From the above it will be appreciated that I have provided a compact machine for 10 stropping razor blades in which blades are inserted and removed safely and expeditiously, and the likelihood of injury to the operator avoided.

I desire it to be understood that various 15 changes and modifications may be resorted to without departing from the spirit of my invention, provided such changes fall within the scope of the appended claims.

What is claimed is:

20 1. A razor sharpener including a supporting frame, sharpening rolls mounted thereon, means to rotate the rolls, a rocking blade holder in the frame, cams turning with said rolls, spring arms on the blade holder in contact with said cams, a slotted frame on the blade holder, and a key also mounted in the supporting frame and having oppositely-projecting fingers working in said slotted frame and adapted when in one position to hold 30 the frame and the blade holder against rocking.

2. A razor sharpener comprising a supporting frame, pairs of sharpening rolls mounted in the frame and disposed at opposite sides of a central supporting space, an oscillating blade holder arranged in said space, means to rotate said rolls, yieldable means associated with the blade rotating means for rocking said blade holder, and 40 means for arresting the movement of the blade holder while permitting of the operation of the rolls.

3. In a razor sharpener, a supporting frame, sharpening rolls mounted therein and being arranged in pairs at opposite sides of a central space, means to rotate said rolls, an oscillating blade holder fitted in the space, cams set at substantially 180° apart and turned by said rolls, a spring yoke having

yieldable ends arranged in the path of said cams and adapted to be alternately operated, said yoke being mounted on the blade holder, an open frame also mounted on said blade holder, and means carried by said supporting frame for engaging said open frame 55 to prevent rocking of the blade holder while permitting of the movement of the rolls.

4. A razor blade sharpener comprising a framework composed of a plurality of spaced apart discs, bars having spaced apart 60 notches adapted to engage with the discs whereby to secure the same together; a tubular casing adapted to be removably slid over the edges of said discs, caps removably fitted upon the ends of said tubular casing, stropping means carried by said discs, means to rotate said stropping means, an oscillating blade holder supported by said discs and mounted between the stropping means, and means for imparting rocking movement to 65 said blade holder while the stropping means is in operation.

5. In a razor blade sharpener, the combination of a framework composed of a plurality of discs having cut away portions in 70 their edges, series of bars having spaced apart cut out portions adapted to interfit with the cut out edges of the discs, the outer faces of the bars adapted to lie flush with the edges of the discs, a tubular casing 75 adapted to be removably slipped over the edges of said discs and the outer faces of said bars, removable caps fitting over the ends of said tubular casing, stropping rolls supported by the discs within the casing, 80 gearing for rotating the rolls mounted at one side of one of the discs, a blade holder 85 rockingly supported by certain other of the discs, means for rocking the blade holder, means for rotating the rolls and for actuating 90 said last named means, and means whereby the rocking movement of the blade holder may be arrested.

AXEL RUDOLPH SALSTROM.
